CLAIM

The ornamental design for a tray for plant pots or the like, as shown and described.

DESCRIPTION

FIG. 1 is a top perspective view of a tray for plant pots or the like showing my new design, the cards being shown in broken lines for illustrative purposes only;

FIG. 2 is a bottom perspective view thereof;

FIG. 3 is an enlarged side elevational view thereof;

FIG. 4 is an enlarged end elevational view thereof;

FIG. 5 is a sectional view taken in the direction of the arrows on line 5—5 of FIG. 4, the cards being shown in broken lines for illustrative purposes only.

FIG. 1

FIG. 2

FIG. 3

FIG. 4

FIG. 5
